MATERIAL HANDLING VEHICLE

Salvatore F. Aiello, Racine, and Eugene Olson, Wausau,
Wis., assignors to Loed Corporation, Wausau, Wis.

Filed Oct. 30, 1972, Ser. No. 302,138

Term of patent 14 years

Int. Cl. D12—05

U.S. Cl. D12—57

FIG. 1.

FIG. 2.

FIG. 4.

FIG. 5.

FIG. 1 is a left side elevational view of a material handling vehicle showing our new design, with a portion of the front left fork being broken away for convenience of illustration;

FIG. 2 is a right side elevational view thereof, with a portion of the front left fork being broken away for convenience of illustration;

FIG. 3 is a right side elevational view thereof, with the telescoping boom shown in a partially extended position and in a partially upwardly tilted position;

FIG. 4 is a front elevational view thereof, with the hoist being omitted for ease of illustration;

FIG. 5 is a rear elevational view thereof; and

FIG. 6 is a top plan view thereof.

We claim:

The ornamental design for material handling vehicle, as shown and described.
